(57) **CLAIM**

(21) Appl. No.: **29/187,173**

The ornamental design for an independently adjustable height work support, as shown.

(22) Filed: **Jul. 29, 2003**

DESCRIPTION

(51) LOC (7) Cl. **25-04**

FIG. 1—Is a right side view in extended position showing the new design;

(52) U.S. Cl. **D25/67**

FIG. 2—is a left side view thereof;

(58) Field of Search D25/62, 67; 182/181.1, 182/153, 183.1, 186.6

FIG. 3—is a left end view thereof;

(56) **References Cited**

FIG. 4—is a right end view thereof;

U.S. PATENT DOCUMENTS

FIG. 5—is a side view thereof in lowered position;
